CONTROL SYSTEM

Kendall Clark, South Bend, Ind., assignor to
International Engineering Corporation, Chi-
cago, Ill., a corporation of Illinois

Refiled for abandoned application Serial No.
128,739, March 3, 1937. This application Jan-
uary 3, 1938, Serial No. 183,148

6 Claims. (Cl. 158—28)

This invention relates to control systems, for oil burners and the like, and especially to systems including thermostatically controlled circuits for turning on and off the motor and ignition means 5 of the burner.

An object of the invention is to provide simple and effective means for first actuating both the motor and the ignition means and then turning off the ignition means after the burner ignites, 10 without interfering with continued operation of the motor, and finally turning the motor off automatically on failure of ignition (regardless of room temperature) after an interval determined by the time normally required to actuate a stack 15 switch or the like affected by the heat of the burner. Preferably the ignition circuit includes a safety device which renders the entire system inoperative after prolonged operation of the ignition means without igniting the fuel at the burner.

Important features of novelty relate to the structure of the stack switch, as well as its arrangement in the control circuit. These features, and various other structural features and desirable arrangements, will be apparent from the following description of the illustrative embodiments 25 shown in the accompanying drawings, in which:

Figure 1 is a longitudinal section of my novel stack switch;

Figure 2 is a transverse section on the line 30 2—2 of Figure 1;

Figure 3 is a partial exploded view showing in detail several elements of my novel switch;

Figure 4 is a wiring diagram of a novel oil burner control circuit using resistance ignition 35 and my novel switch and adapted to control a splitphase induction motor;

Figures 5 and 6 are elevational and sectional views respectively of two modifications of a novel resistance ignition unit to be used in the circuit of Figure 4; and

Figures 7, 8, and 9 are wiring diagrams of modified control circuits employing my novel switch and spark ignition, and adapted to control a split phase induction motor, a repulsion induction motor and a shaded pole induction motor respectively.

Referring to Figure 1 of the drawings there is shown a chimney or stack 10 through which the gases of combustion from an oil burner are adapted to pass. The oil burner may be of any type such as, for example, that shown in my copending application Serial No. 117,459, filed December 24, 1936, in which a motor is adapted to actuate a fan and fuel pump to supply a combustible mixture of oil and air to a furnace and in which

the starting of the motor immediately, or at least within a very short time, starts the flow of combustible mixture.

My novel stack switch, indicated generally by the numeral 12, is mounted on the stack by 5 means such as a flanged fitting bolted thereto and having a circular opening coincident with an opening in the stack through which passes a tubular member 16 removably secured in the flange 14 by any desired means, such as a set screw 18, so 10 that one end is inside the stack and the other outside.

A flattened portion 20 on the inside end of the tube 16 provides a seat to which is brazed or welded one end of a helical bi-metallic element 15 22 of less diameter than the tube 16 so that the switch may be removed bodily from the stack by loosening the set-screw 18 and withdrawing the switch from the flange 14.

Threaded into the outer end of the tube 16 is 20 a combination bolt and bushing 24 having a head between which and the tube 16 are compressed: first, the bottom of a cup-shaped switch housing 26; and second, a series of heat radiating fins 28 preferably of copper, fitting tightly to the 25 bushing and spaced by washers 30 of any suitable non-heat-conducting material.

In the bushing 24 is journaled a long shaft 32 having formed on its inside end (i. e., inside the stack) a slot 34 (Fig. 3) adapted to receive 30 and have secured therein the bent-in, free end of the bimetal helix 22, and having at its other end, projecting into the switch housing 26, first a squared portion 36; and second, a cylindrical pin 38.

The squared portion 36 engages a clutch to be described below, and the pin 38 forms a bearing for one end of a shaft 40 the other end of which is provided with a portion 42 of decreased diameter journaled in a closure 44 for the open end 40 of the cup. This closure is preferably made of electrical insulating material. The central part of the shaft 40 is supported by an insulating partition 43 separating the switching elements from the clutch elements previously mentioned.

A switch arm 46 formed of a strip of brass or the like having contact points 48 secured on opposite faces adjacent one end and having its other end formed parti-cylindrically passes through a slot 50 in the shaft 40. A spring 52 urges the 50 arm radially so that the parti-cylindrical end maintains continuous contact with a main contact 54 secured to the closure 44. This contact is formed on an arc having its center at the center of the shaft, and it has humps 56 and 58 adjacent 55

each end of the arc adapted to act as latches for the arm 46 in its respective contact engaging positions.

- 5 The contact 54 is secured to the closure 44 by means of a rivet 60 having a long prong on the outer end adapted to receive a plug-in socket or the like 62, and similar rivets 64 and 66, also adapted to coact with the socket, carry contacts 68 and 70 respectively which engage with the contacts 48 in opposite position of the switch arm. The contacts 68 and 70 are resiliently mounted by means of spiral springs 72 secured in the inside projections of the rivets 64 and 66 respectively.
- 10 15 Another contact 74 is mounted on a spring support 76 secured in the rivet 66 which passes over the switch arm 46 so that the contact is positioned directly behind the contact 70 permitting the switch to close and open two circuits simultaneously.

An important minor feature of the invention is a novel slipping clutch connection between the shafts 32 and 40 comprising a C-shaped stamping 78 pierced at the back of the C with a square hole 80 fitting on the squared portion 38 of the shaft 32 and having the arms of the C closely formed around the shaft 40 and held in tight frictional engagement therewith by a garter spring 82. This clutch permits continued expansion or contraction of the bimetallic element 22 after the switch has been operated.

In operation, when no gases are passing through the stack 10 the bimetal element 22 is cold and urges the arm 46 in the counter-clockwise direction so that contacts 48, 68 and 74 are closed and the partly-cylindrical end of the arm 46 is to the right of the hump 58. The switch is now said to be on the "cold" side.

In this position the burner is brought into operation, and the gases of combustion passing the bimetal element 22 cause it to wind up more closely urging the arm 46 in the clockwise direction, but it is held in place by the hump 58 until the force exerted is sufficient to compress the spring 52, whereupon the arm snaps to the other side closing the contacts 48 and 70, the partly-cylindrical end of the arm 46 passing over the hump 56. This is called the "hot" side of the switch.

50 Whenever gases cease to flow in the stack the bimetal element cools and unwinds and the arm snaps in the opposite direction. An important minor feature of the invention resides in making the hump 58 higher than the hump 56 whereby 55 in returning to the "cold" side insufficient energy is stored in the bimetal element to move the arm over the hump 58, thus creating a delay period in which the bimetal element must cool further and store up sufficient energy to lift the arm over 60 the hump 58 before the "cold" side contact is made.

While the foregoing refers to a specific embodiment it is clear that a great number of variations in arrangement of contacts and delay action 65 might be worked out for particular circuit requirements.

Referring now to the control circuit diagram of Figure 4 there are shown the two wires 82 and 84 of a single-phase A. C. line. Connected in 70 series in the line 82 is the usual room thermostat 86 of any desired type adapted to close the circuit when heat is called for, together with a limit switch 88 (adapted to open the circuit upon over pressure in a steam heating system or upon excessive temperature in hot air and hot water sys-

tems), and a time delay switch 90. The wire 82 terminates at the main contact 54 of the stack switch 12.

In this case the time delay switch is illustrated as a bi-metal element 92 anchored at one end and closing the circuit by a contact at its other end, a heating coil 94 on a separate circuit and a latch 96, adapted to hold the bimetal element away from the contact when deformed by the heat in the coil 94, thereby requiring manual operation to reestablish the circuit.

The other line 84 terminates at the junction of two parallel circuits one of which 85 has connected therein, in series, the "running" or inductive winding 98 of a split phase induction motor 100 which operates the fuel pump and fan (not shown) of the oil burner. The wire 85 terminates at the prong 66 of the stack switch and is thus connected to both contacts 68 and 74 so that contact is made with it on both the "hot" and 20 cold sides of the switch.

The other parallel circuit 102, connected to the line wire 84, has connected in series in it a resistance ignition element 104 which may be of the type described below, the "starting" or resistive winding 106 of the motor 100 and the heating coil 94 of the time delay switch 90. The line 102 terminates at the contact 70 of the stack switch.

It will be noted that instead of employing the 30 usual resistance element in connection with the splitphase coil, whereby energy is wasted, the ignition and delay switch resistances are substituted thereby causing the heretofore wasted energy to serve a useful purpose.

In operation, assuming the room thermostat to be open the stack switch will be on the "cold" side with the contact 48 in engagement with contacts 68 and 74. As the space to be heated grows colder, the room thermostat 86 closes the circuit 82 and current flows through both circuits 85 and 102 energizing the starting and running windings 106 and 98 of the motor 100 and thereby starting the motor to supply the combustible mixture to the furnace.

At the same time the ignition element 104 is heated by the current in the circuit 102 and ignites the mixture. With combustion established, the hot gases in the stack 10 gradually heat up the bimetallic element 22 until the switch snaps to the "hot" side. This opens both circuits 85 and 102 but instantaneously reestablishes circuit 85 through the contact 70 and the motor 100 continues to run, energized solely by the "running" winding 98 in the manner of a simple single phase induction motor.

When the space being heated is warm enough the room thermostat 86 breaks circuit 82 stopping the motor. The gases in the stack gradually cool off permitting the switch 12 to return to the 60 "cold" side.

If the current should only be interrupted long enough for the motor to stop and then reestablished the motor could not start until the furnace has cooled and the stack switch snapped back to 65 the "cold" position whereupon ignition is supplied and the burner restarts in the normal manner.

If combustion fails to take place the continued flow of current through the circuit 102 heats up 70 the bimetal element 94 of the time delay switch 90 opening the circuit 80 and throwing the whole system out of operation until the trouble is discovered and the switch 90 reset.

If combustion should fail while the burner is in 75

operation, due, e. g., to clogging of the oil spray nozzle, or air inlet openings, or due to oil pump breakage or fan breakage, the cooling of the stack switch bimetal element 22 will return the switch to the "cold" side and restart the burner. The previously described delay in returning permits the furnace to cool to the point where it is safe to restart without danger of explosion in event that the continued running of the motor, while the stack switch was cooling off enough to open the circuit 85, has resulted in discharging a lot of oil into the furnace. Upon restarting, if the condition which caused failure of combustion has not been remedied the time delay switch 80 will lock out the system.

It will be noted that this system provides intermittent ignition providing long life for the ignition element.

Figure 5 shows a novel and desirable type of ignition element 104 adapted for use in this system, the particular feature of which is that it automatically limits its temperature. It comprises a rod 108 of silica or similar material which becomes a conductor at elevated temperatures and the resistance of which decreases with increase of temperature. The rod is supported in brackets 110 which in the circuit of Figure 4 would be connected in the circuit 102. A resistance winding 112 of chrome nickel wire or similar material is connected to the brackets and wound around the rod. When a certain temperature is reached the rod 108 becomes conducting shunting the current from the wire 112.

In Figure 6 the resistance wire 112 is enclosed in a silica tube 108 thereby eliminating oxidation and causing the element to last indefinitely.

The circuit of Figure 7, in which identical elements have the same reference numerals, is similar to that of Figure 4 with the exception that intermittent spark ignition is used instead of resistance ignition. It is desirable to apply full line voltage to the primary of the ignition transformer, consequently, instead of being connected in series with the circuit 102, a circuit 114 paralleling 102 is employed in which the primary of the ignition transformer 116 is connected. An ignition spark gap 118 is connected across the high voltage secondary of the transformer. The operation is the same as in Figure 4.

The circuit of Figure 8 is for controlling a burner employing a repulsion induction motor 300 and in this figure elements corresponding exactly to elements in the previous circuits are designated by the same reference numerals and corresponding elements are indicated by the same reference numerals plus 200.

As is well known in the art this type of motor comprises a standard single phase induction stator winding 298, and a squirrel cage or wound induction rotor (here shown as a squirrel cage rotor) on which is superimposed a commutator winding having brushes 120 set generally 180 electrical degrees from the axis of the reversing field created by the induction winding.

To obtain starting torque the commutator brushes 120 are short circuited. When the motor approaches synchronous speed the short circuit may be opened and the motor operates as a single phase induction motor.

Consequently the brushes 120 have been connected in a circuit 302 between terminals 64 and 66 of the stack switch so as to be short-circuited on the "cold" side and open circuited on the "hot" side of the switch.

With some loss of starting torque the time delay

switch heating coil 94 and the ignition transformer 116 may be connected in series in the line 302 and supplied with current by the induced voltage in the commutator winding.

If the loss of starting torque is too great, ignition current may be supplied by means of a low-loss relay as shown in the circuit of Figure 9.

Figure 9 shows my novel circuit for a shaded pole motor. In this figure elements identical to those in preceding figures are designated by the same reference numerals as used where the element first appears plus 300.

This type of motor may have a squirrel cage rotor and a stator with salient poles each of which is divided into unequal parts by a slot paralleling the rotor axis. The main field winding 398 is wound around the whole pole and the shading winding 406 comprises a few turns around the smaller portion of the pole. This winding is usually short circuited and has a voltage induced in it by the current in the main field which unbalances the field and creates a starting torque.

In this novel circuit, leads are taken from the shading winding and connected in the circuit 402 extending between the terminals 60 and 64 as in the preceding figure so as to be short-circuited when the switch is on the "cold" side and open circuited when on the "hot" side.

In series in the circuit 402 are the relay switch 30 heating coil 94 and a low loss relay 122, the armature 124 of which is adapted to close a circuit 126 connected across the power lines 82-84 and in which is connected the ignition transformer 116. It is absolutely necessary to provide the relay 122 in this circuit as the shading coil induced voltage is insufficient to supply ignition current. It is believed unnecessary to describe in detail the operation of the circuits of Figures 8 and 9 as they are in all respects analogous to that of Figure 4.

While several illustrative embodiments have been described in detail, it is not my intention to limit the scope of the invention to those particular embodiments, or otherwise than by the terms 45 of the appended claims. The present application is a refiled of my application No. 128,739, filed March 3, 1937.

I claim:

1. A control system for an oil burner, or the like, comprising, in combination with the burner and its motor and igniter, said motor having starting and running windings, a source of electric current and a room-thermostat control therefor, two circuits one of which includes the motor starting winding and igniter and the other of which includes the motor running winding and not the igniter, a safety device in said one circuit actuated by operation of the igniter for more than a predetermined time and which when so actuated renders the entire system inoperative, and a control device including thermostatic means affected by heat from the operation of the burner and a switch actuated thereby when the burner is cold to connect said circuits in parallel to said source of current ready for operation of the motor and igniter when the room-thermostat calls for heat and actuated after the burner has been in operation a relatively short time to disconnect said one circuit from said source and to leave said other circuit connected thereto.

2. A control system for an oil burner, or the like, comprising, in combination with the burner and its motor and igniter, said motor having

starting and running windings, a source of electric current and a room-thermostat control therefor, two circuits one of which includes the motor starting winding and igniter and the other of which includes the motor running winding but not the igniter, and a control device including thermostatic means affected by heat from the operation of the burner and a switch actuated thereby when the burner is cold to connect both of said circuits to said source of current ready for operation of the motor and igniter when the room-thermostat calls for heat and actuated after the burner has been in operation a relatively short time to disconnect said one circuit from said source and to leave said other circuit connected thereto.

3. A control system for an oil burner or the like comprising, in combination with the motor and ignition circuits of a burner, said motor having a starting winding and a running winding in different ones of said circuits, a thermostatically-controlled device affected and actuated by heat from the burner when it is on and which device automatically closes the circuits through both of the motor windings and through the ignition when it is cold and which, as it heats up when the burner starts, opens the circuit through the

starting winding and the ignition while leaving the circuit through the running winding closed.

4. An oil burner or the like comprising in combination with a repulsion induction motor having a commutated wound rotor, an electrically energized ignition element, and means to energize the ignition element in an electrical series circuit with only the commutated wound rotor.

5. An oil burner or the like comprising in combination with a split phase induction motor having starting and running windings, electric ignition means for igniting the burner, and means to energize the electric ignition means in an electrical series circuit with only the starting winding of the motor.

6. An oil burner or the like comprising in combination with a split phase induction motor having starting and running windings, electric ignition means for igniting the burner, electrical switching means to start the burner and the motor with the starting winding of the motor and the electric ignition means electrically energized in series, and thermostatic switching means responsive to an increase in the heat from the burner to deenergize the starting winding of the motor and the ignition means.

KENDALL CLARK.
